UNITED STATES PATENT OFFICE.

CHARLES MOSCH, OF PORTLAND, OREGON.

DOOR.

1,085,931.

Specification of Letters Patent.

Patented Feb. 3, 1914.

Application filed March 9, 1912. Serial No. 682,825.

To all whom it may concern:

Be it known that I, CHARLES MOSCH, a subject of the Emperor of Germany, residing at Portland, in the county of Multnomah and State of Oregon, have invented certain new and useful Improvements in Doors, of which the following is a specification.

This invention relates to improvements in doors, and the primary object of the invention is to provide a door which may be utilized either as a solid panel or glazed door in cold weather or may be utilized as a screen door in hot weather, without being removed from its hinges.

A secondary object of the invention is to provide a slideable panel or door member and simple and efficient means for operating the said panel and holding it in its raised position.

A further object of the invention is generally to provide a door which will be neat in appearance and which will be strong and durable and inexpensive to produce.

The invention is fully illustrated in the accompanying drawings and will be herein-after described in detail, the novel features of the same being subsequently pointed out in the appended claim.

In the drawings: Figure 1 is an elevation of a door embodying my present invention; Fig. 2 is a vertical section of the door taken adjacent one of the stiles; Fig. 3 is a similar view showing the slideable panel in a different position; Fig. 4 is a view showing parts of the device in elevation and parts in section, with intermediate portions broken away whereby to more clearly show the detail construction and arrangement of the essential parts of the invention; Fig. 5 is a sectional view taken on the line 5—5 of Fig. 4; Fig. 6 is a horizontal section taken on the line 6—6 of Fig. 1; Fig. 7 is a detail perspective view showing a portion of the edge of the slideable panel and the means for attaching the same to the operating cable; Fig. 8 is a detail view showing one of the pulls or handles on the sliding panel.

In carrying out my invention, I employ a frame consisting of the stiles 1 and the upper and lower rails 2 and 3 and intermediate bar 4 connecting the stiles. The intermediate bar 4 is recessed at its ends as shown by dotted lines in Figs. 1 and 4, and holding or retaining strips 5 are secured to the stiles and extend across the rails and the said intermediate bar so as to impart a some-

what ornamental appearance to the door and also to permit access to the operating parts as will be presently set forth. These several retaining strips are secured to the door frame by screws 6, preferably, in order that the removal and replacing of the bars will not cause undue injury to the material of which the frame is made. The lower portion of the frame, that is to say, the part between the lower rail 3 and intermediate bar 4 may be finished in any desired manner to present a solid panel 7 while the portion between the intermediate bar and the upper rail is left open to be covered by a sliding panel hereinafter more particularly described.

The inner or facing edges of the stiles are provided longitudinal grooves 8 in which the operating cord or cable 9 plays, the said cord constituting an endless belt passing around pulleys 10 mounted in recesses 11 near the lower ends of the stiles and similar pulleys 12 secured rigidly on a shaft or winding rod 13 which extends through the upper rail and is journaled in bearing plates 14 secured in recesses 15 near the upper ends of the stiles. The upper rail is provided with a longitudinal recess or cavity or chamber 16 to accommodate a shaft or winding rod 13 and a screen 17, preferably of wire netting, is secured to the said shaft or winding rod and adapted to wind upon or unwind therefrom in the operation of the invention. A longitudinal slot 18 is formed in the lower edge of the rail and the side walls of the said slot diverge upwardly, as shown at 19 in Figs. 2 and 3, so as to accommodate the inclined position assumed by the downwardly extending portion of the screen 17 as the same is wound upon the shaft. The lower edge of the said screen is secured to a sliding panel or frame 20 which is mounted between the stiles 1 and adapted to move downwardly through the intermediate bar 4 and into a chamber 21 formed behind the lower panel 7, as will be readily understood upon reference to Figs. 2 and 3. This panel or frame 20 may be equipped with an ornamental solid opaque plate, but is preferably glazed, a pane of glass being indicated in the drawings. The pane 22 is secured within the frame by means of molding strips 23 fitting against the pane and upon rabbets formed in the frame, and the lower edge of the screen 17 is secured in the upper edge of the said frame 20 by means of a molding strip

24 in a similar manner, as clearly shown. The upper retaining strips 5 extend over the chamber 16 in the rail so as to protect the same against the entrance of dirt and provide removable covers for the said chamber so that access to the parts may be readily had when necessary.

Molding strips 25 are secured to the lower edge of the rail and spaced apart so as to furnish a groove or recess to receive the upper edge of the slideable panel when the same is raised and the lower edge of the rail constitutes a stop to limit said upward movement, all of which will be readily understood upon reference to Fig. 2. Similar molding strips 26 are secured upon the upper edge of the intermediate cross bar 4 to form guides for the sliding panel as well as to impart a neat and ornamental finish to the door and additional similar strips 27 are secured to the inner edges of the stiles so as to constitute guides for the panel during its movement. Pivoted upon the inner face of the intermediate bar 4, at or near the upper edge of the same, is a latch 28 which, when the sliding panel is raised, is adapted to swing into the position shown in Fig. 2 whereby the inner end of the latch will project under the panel and consequently support the same in its raised position. When it is desired to lower the panel the free end of the latch is swung downward so that the latch will be disengaged from the panel, as will be readily understood on reference to Fig. 3, and to prevent excessive wear upon the upper end of the panel when the same is in its lowered position, I secure thereto a metal strip 29 against which the end of the latch will bear so that the pressure then exerted by the latch will not indent nor mar the panel. The panel is connected to the operating cable 9 by a screw 30 which passes through the cord 9 so that the movement of the cord will necessarily be imparted to the panel, and to prevent mutilation of the cord or belt by the screw a reinforcing sleeve or ring 31 is fitted around the same at the head of the screw. In the side members of the panel 20 and in the inner faces of said side members, I provide handles or pulls 32 which will furnish a convenient means of grasping the panel when it is desired to raise or lower the same. When the panel is in its lowered position the upper handles or pulls 32 will lie directly behind the recessed ends of the intermediate bar 4 so that if the intermediate retaining strip 5 be removed the handles may be reached and sufficient force applied thereto to move the panel upwardly so that its edge will project above the intermediate bar. The panel may then be readily grasped so that it may be quickly raised to the limit of its upward movement.

65 From the foregoing description, taken in

connection with the accompanying drawings, it is thought that the use and advantages of my improved door will be readily understood and appreciated. In cold weather the panel will be in its uppermost position, indicated in Fig. 2. When the weather becomes hot or, for any other reason, outside air is desired in the room, the latch 28 is depressed and the panel then lowered into the chamber 21, its impact against the bottom of said chamber being cushioned by rubber or other elastic buffers 33 therein, so that damage to any part of the door through dropping or too rapid lowering of the panel will be avoided. To further guard against damage from this source I may provide triangular metallic plates 34 at intervals along the meeting edges of the panel and the lower portion of the stile so that the contact between the overlapping points of said plates will check the descent of the panel. The upper portion of the stile will be beveled to avoid the wearing away of the same by the plates on the panel. As the panel is lowered it will, of course, pull downwardly upon the screen 17 so as to unwind the same and draw it across the space being vacated by the panel so that when the panel reaches its lowermost position the upper portion of the door will be screened to prevent the entrance of flies or other insects but permit thorough ventilation. The belt or cable 9 will follow the movement of the panel and by its engagement with the pulleys will tend to retard the descent of the panel and also will cause the screen to unwind evenly so that wear upon the walls of the slot 18 will be minimized. In raising the panel, the screen would tend to buckle between the upper edge of the panel and the upper rail 2, but this buckling is avoided by the provision of the cable or belt 9 which will positively actuate the shaft or winding rod 13 and thereby cause the screen to wind evenly and smoothly thereon and at a speed determined by the movement of the panel.

It will be readily noted that my improved door is not bulky and that all the operative parts are inclosed in the frame of the door so as to be protected against injury, and as there is no complicated mechanism connected with the door the operation will be easy and frequent repairs will be unnecessary.

It will be understood, of course, that while I have shown and described the invention with particular reference to a door, it is adapted to windows as well and such use of the improvements will involve no departure from the invention.

Having thus described my invention, what is claimed as new is:

A door comprising parallel spaced stiles having vertical grooves in the inside edges,

upper and lower rails, outer and inner retaining strips attached to the stiles and extending below the lower edge of the upper rail to form a screen receiving chamber, outer and inner panels supported upon the lower rail and defining a sash receiving space, a slideable panel vertically movable in said space, a winding shaft disposed in the screen receiving chamber, a screen attached at one end to said winding shaft and at the other to the upper edge of the sliding panel, oppositely disposed pulleys mounted upon the winding shaft, oppositely disposed pulleys mounted in recesses in the inner faces of the stiles and below said panels, an endless flexible connection passing over each pair of upper and

lower pulleys and through the longitudinal groove of the stile, and a connection between one flight of each endless connection and the slideable panel, the pulleys being 20 greater in diameter than the width of the groove through which the two flights of the flexible connection pass whereby to frictionally retard the movement of the flexible connection.

25

In testimony whereof I affix my signature in presence of two witnesses.

CHARLES MOSCH. [L.S.]
